UNITED STATES PATENT OFFICE

99,092

DESIGN FOR HAND WHEEL FOR HAND BRAKES OF RAILWAY CARS

Harvey J. Lounsbury, Glen Ellyn, Ill., assignor to
W. H. Miner, Inc., Chicago, Ill., a corporation
of Delaware

Application February 7, 1936, Serial No. 61,016

Term of patent 14 years

To all whom it may concern:

Be it known that I, Harvey J. Lounsbury, a citizen of the United States, residing at Glen Ellyn, in the county of Du Page and State of Illinois, have invented a new, original, and ornamental Design for Hand Wheel for Hand Brakes of Railway Cars, of which the following is a specification, reference being had to the accompanying drawing, forming part thereof.

Figure 1 is a plan view of a hand wheel for hand brakes of railway cars, showing my new design.

Figure 2 is a side elevational view.

I claim:

The ornamental design for hand wheel for hand brakes of railway cars, as shown.

HARVEY J. LOUNSBURY.
